FIG. 11

ARTHUR E. SMITH

BY

B. J. Murphy

ATTORNEY.

UNITED STATES PATENT OFFICE.

ARTHUR E. SMITH, OF LOS ANGELES, CALIFORNIA.

SYRINGE CONSTRUCTION.

Application filed December 17, 1927. Serial No. 240,795.

This invention relates to improvements in hypodermic syringes.

The general object of this invention is to provide an improved syringe wherein the substance to be ejected is contained in a cartridge-like ampule which is provided with a slideable stopper, and wherein means is provided for automatically and for correctly positioning an ampule in the syringe when the operating member of the syringe is arranged in an operative position; and wherein in the process of injecting, the various parts of the syringe coact to move the stopper relative to the ampule to force out the contents of the ampule.

Another object of this invention is to provide an improved syringe having an ejector plunger which is adapted to enter a constricted portion of an ampule contained therein with means for automatically and correctly positioning the ampule before the plunger enters the constricted portion of the syringe.

An additional object of the invention is to provide a novel means for centering an ampule in a syringe.

Other objects of this invention will be apparent from the following description taken in connection with the accompanying drawings, wherein:

Fig. 1 is a central longitudinal section through my improved syringe showing an ampule therein, and showing the ejecting plunger about to be operated to move the ampule stopper to eject the contents of the ampule.

Fig. 2 is a side view of the syringe showing the positions of the various elements after the contents of the ampule have been ejected.

Fig. 3 is a top plan view of the syringe body with the cap, ejecting plunger mechanism, and the ampule removed.

Fig. 4 is an enlarged fragmentary central longitudinal section through the breach of the syringe showing a small ampule in the barrel and showing how the centering device acts to position a small ampule.

Fig. 5 is a section taken on line 5-5 of Fig. 4.

Fig. 6 is a side view of a two compartment

ampule such as is adapted to be used in connection with my improved syringe.

Fig. 7 is a view similar to Fig. 6 showing the manner of mixing the vehicle with the drug in the ampule.

Fig. 8 is an enlarged central vertical section through the stopper of the ampule.

Fig. 9 is an enlarged central vertical section through the end of the vehicle transfer probe.

Fig. 10 is a side view partly in section of a modified form of ampule such as may also be used in connection with my improved syringe, and

Fig. 11 is a side view partly in section of another form of ampule which may be used in my improved syringe.

Referring to the drawings by reference characters I have indicated a hypodermic syringe embodying the features of my invention generally at 10. This syringe comprises a hollow body portion or barrel 11 preferably of metal and having screw threads 12 provided at one end and having its other end left plain. Adjacent one end of the barrel 11 a finger grip cross bar 13 is provided and in the barrel 11 oppositely disposed elongated apertures 14 are arranged. Between these apertures and on the inner wall opposed grooves 15 are provided.

The end of the syringe opposite the cross bar 13 is provided with a tip 16 which is in threaded engagement with the screw threads 12 of the barrel. This tip 16 has a reduced end 17 and is provided with a tapered recess 18 which communicates with an aperture 19 which extends through the reduced end 17. A hypodermic needle 20 is adapted to be positioned on the reduced end 17 of the tip 16 and the end 17 may either be threaded or tapered as shown.

The end of the syringe opposite the tip 16 is adapted to be closed by a cap 21 which has a sliding fit in the syringe barrel 11 and is adapted to be held in closing position by frictional engagement with the syringe barrel. The cap 21 is shown as including a recess 22 in which is provided a boss 23 through which an aperture 24 provided in the cap extends. The boss 23 is provided with a cir-

55

60

65

70

75

80

85

90

100

cumferential groove 25 (see Fig. 5) and in the groove oppositely disposed slots 26 are provided which extend through the body of the boss into the aperture 24 (see Figs. 4 and 5). A spring clip 27 is positioned in the slots 26 and a portion of it extends into the aperture 24 and resiliently engages a plunger rod (to be presently described) which passes through the aperture. The cap 21 also includes at its lower end a reduced flange 28.

Positioned in the aperture 24 of the cap I provide a plunger rod 29 which includes an enlarged thumb piece 30 and an enlarged screw threaded head 31 in which is provided a recess 32. The clip 27 of the cap engages the plunger rod 29 and the tension on the plunger rod resiliently holds it in set relation to the cap.

20 Mounted on the plunger rod 29 between its head 31 and the cap 21 I provide an ampule centering device 33 which has a sliding fit in the barrel 11 and includes an aperture 34 for the passage therethrough of the plunger rod 31. The centering device 33 is shown as provided with a circular groove 35 on its top face and provided with a conical recess 36 in its lower face which is adapted to communicate with the aperture 34. At the juncture of the aperture 34 and the conical recess I provide screw threads 37 of a size corresponding to the size of the screw threads on the plunger rod head 31. On opposite sides of the centering device I have shown two sets 35 of apertures 38 in which are mounted coiled compression springs 39 and balls 40. The balls 40 are shown as adapted to be maintained in place by rings 41 which are secured in place after the springs and the balls have 40 been placed in position in the apertures 38.

When the centering device 33 is positioned in the barrel 11 of the syringe the balls 40 are adapted to be positioned in the grooves 15 in the syringe barrel and will frictionally engage the surfaces of the grooves and hold the centering device in any position at which it is stopped.

When it is desired to operatively position the cap 21, the plunger rod 29 and the centering device 33 in the syringe, it is preferable to screw the head 31 of the plunger rod into the screw threads 37 on the centering device 33 and then move the cap 21 into contact with the centering device so that the flange 28 on 55 the lower end of the cap fits within the groove 35 on the upper face of the centering device as shown in Fig. 4. The cap 21 is then grasped and the centering device is placed in the end of the syringe so that the balls 40 are positioned in the grooves 15 and then 60 the cap is moved into operative position in the syringe barrel 11. By unscrewing the plunger rod head 31 from the centering device 33 the plunger rod 29 may be moved 65 within the barrel 11. When removing the

cap 21, plunger rod 29 and the centering device 33 from the syringe it is preferable to again bring them into the same relationship as when inserting them in the syringe as previously described.

70 In Figs. 6 and 7 I have indicated generally at 45 the ampule which I have shown as used in the syringe in Figs. 1 and 2. This ampule 45 as shown comprises two separate containers or compartments 46 and 47 which are 75 preferably made of glass, fused together and constricted at their juncture as indicated at 48.

80 The end of the compartment 46 is closed by a bulbous portion 49 and at the juncture 85 of the compartment 46 and the bulbous portion 49 a constricted portion is provided as indicated at 50. The end of the compartment 47 is provided with a tapered neck 51 which terminates in a closed tip 52.

85 Between the two compartments 46 and 47 and at the constriction 48 a metallic seal 53 is provided. This metallic seal is preferably a disk shaped platinum partition and may be fused in position when manufacturing the 90 ampule. In the compartment 47 and adjacent the constriction 48 I provide a stopper indicated generally at 54 and shown in detail in Fig. 8. This stopper is preferably positioned in the compartment 47 before the tapered 95 neck 51 and tip 52 are formed. Surrounding the tapered neck 51 I provide a resilient collar 55 which is preferably made of a good grade of rubber.

100 To render the bulbous portion 49 readily separable from the compartment 46 I preferably weaken the constricted portion 50 by scoring or etching it as at 56. To render the compartments 46 and 47 readily separable from one another I may weaken the constricted portion 48 by etching it as at 57 and to render the tip 52 readily separable from the neck 51 I may also weaken it by etching it just below the resilient collar as at 58.

105 The contents of the compartment 46, such as the vehicle 59, is preferably placed therein before the bulbous portion 49 is closed and the contents of the compartment 47, such as a drug 60, is placed therein before the tip 52 is closed. Also, before the tip 52 is closed 110 the compartment 47 is preferably exhausted to a state of partial vacuum.

115 The stopper 54 is preferably made of a good grade of rubber and includes a body portion 61 having a protruding tip 62 extending therefrom. At the juncture of the body portion and the tip a semi-circular groove 63 is provided so that when the stopper is used as a piston to expel the contents of the ampule the pressure exerted upon the stopper by the contents of the ampule will cause the lower edge of the stopper to tightly grip the inner side walls of the ampule and prevent any of the ampule contents from 120 passing the stopper.

Grooves 64 are preferably provided in the sides of the body 61 and a lubricant 65, such as glycerine, may be placed in the grooves so as to lessen the friction of the stopper 5 against the side walls of the ampule when it is moved therein.

A metallic tube 66 which may have integral radially extending fins 67 is provided in the body 61 and is preferably positioned there- 10 in at the time of moulding the stopper.

To prepare the ampule 45 for use in my improved syringe 10 the bulbous portion 49 is broken off at the etching 56 and a probe 70 is inserted through the opening at the 15 constriction 50.

The probe 70 is shown in detail in Fig. 9 and preferably comprises a solid metal stem 71 having a recess 72 therein at one end into which radially disposed apertures 73 form a 20 passageway from the outside. One end of a hollow reduced needle 74 is inserted and secured in the recess 72 and the opposite end of the needle is preferably sharpened as at 75. The needle 74 is of a size to pass through the 25 aperture in the tube 66 but the stem 71 will not pass through the aperture in the tube 66 but will abut the end of the tube 66.

When the probe 70 has been inserted into the compartment 46 it is moved downward so 30 that the needle 74 fractures and passes through the metallic partition 53 into the aperture of the hollow tube 66 of the stopper, through the solid portion of the stopper tip 62 and into the compartment 47, as clearly 35 shown in Fig. 7.

When the needle 74 has sufficiently entered the compartment 47 it will be stopped by the end of the stem 71 abutting the end of the tube 66. The needle 74 extends a certain pre- 40 determined distance from the end of the stem 71 so that when the stem abuts the end of the tube 66 it is sufficiently clear of the stopper tip 62 to allow the vehicle contained in the compartment 46 to be drawn by the vac- 45 um in the compartment 47 through the apertures 73, into recess 72, through the hollow needle 74 and be freely discharged into the drug compartment 47, thus mixing the ve- 50 hicle and the drug into a single solution as shown in Fig. 7.

After the vehicle and the drug have been mixed the probe 70 is withdrawn and the compartment 46 is separated from the compartment 47 at the etching 57. The tip 52 55 is then separated from the compartment 47 at the etching 58 and the compartment 47 is then ready for use as an ampule in my syringe 10.

To insert an ampule in my improved 60 syringe 10 the cap 21, together with the plunger rod 29 and the centering device 33, is removed as previously described. The ampule is then inserted in the syringe barrel 11 so that the collar 55 is positioned in the tapered recess 65 18 of the tip 16 and then the cap 21, plunger

rod 29 and the centering device 33 are again operatively positioned in the syringe barrel 11 as previously described. The plunger rod 29 is then moved towards the ampule until the centering device 33 abuts the end of the 70 ampule and centers it. Then the plunger rod is unscrewed from the centering device and moved through the opening at the constriction 50 until it abuts the stopper 54. When the end of the plunger rod 29 abuts the stopper 75 54 it contacts with the uppermost fin 67 and the protruding end of the tube 66 is positioned in the recess 32 of the plunger rod, thus preventing the end of the plunger rod from skidding to one side and tilting the 80 stopper.

Upon further movement of the plunger rod 29 towards the tip 16 the plunger will force the stopper 54 towards the tapered neck 51 of the ampule and cause the stopper to act 85 as a piston to expel the contents of the ampule into the hypodermic needle 20.

The pressure of the balls 40 in the centering device 33 against the surface of the grooves 15 in the syringe barrel 11 will maintain the centering device in engagement with the end of the ampule throughout the ejecting operation and the spring clip 27 will maintain the plunger rod 29 in whatever position it may be stopped at during an ejecting 95 operation.

The pressure required to move the stopper 54 to expel the contents of the ampule will wedge the collar 55 in the tapered recess 18 of the tip 16 and form a fluid tight seal between the end of the ampule and the syringe. 100

In Fig. 10 I have indicated a modified form of ampule for use in my syringe 10 generally at 77. This ampule 77 includes a body portion or compartment 78 which is closed at one end by a bulbous portion 79 and the opposite end is provided with a tapered neck 80 which terminates in a closed tip 81. At the juncture of the bulbous portion 79 and the compartment 78 a constricted portion is provided as 110 indicated at 82. In the compartment 78 and adjacent the constriction 82 I provide a stopper 83 which is similar to the stopper 65 and is provided with a metallic stud 84 which extends above the upper face of the stopper. Surrounding the tapered neck 80 I provide a 115 resilient collar 85 which is preferably made of a good grade of rubber.

To render the bulbous portion 79 readily separable from the compartment 78 I preferably weaken the constricted portion 82 by scoring or etching it as at 86 and to render the tip 81 readily separable from the neck 80 I may also weaken it by etching it just below the resilient collar as at 87. 120

To prepare the modified ampule 77 for use in my syringe 10 it is only necessary to break the bulbous portion 79 off at the etching 86 and to break the tip 81 off at the etching 87. The insertion and operation of this ampule 77 130

in the syringe 10 is the same as that previously described in connection with the ampule 45.

In Fig. 11 I have indicated generally at 90 another modified form of ampule for use in my syringe 10. This ampule 90 includes a body portion or compartment 91 provided at one end with a tapered neck 92 which terminates in a closed tip 93. The opposite end of 10 the compartment 91 is formed plain and open and may be covered if desired by a gelatinous cap 94. In the compartment 91 adjacent the open end thereof I provide a stopper 95 which is made of a good grade of rubber. This stopper 95 has a metallic disk 96 positioned on its upper face which includes a stud 97 projecting upwardly therefrom and a pair of depressed loops 98. The disk 96 is joined to the stopper 95 at the time of moulding the stopper 15 and the loops become imbedded in the body of the stopper and retain the disk 96 in position on the stopper.

To render the tip 93 readily separable from the tapered neck 92 I may weaken it by etching it as indicated at 99. A resilient collar 100 is provided on the tapered neck 92 just 20 above the etching 99.

To prepare the ampule 90 for use the cap 94 is removed and the tip 93 is broken off at 25 the etching 99. The insertion and operation of this ampule 90 in the syringe 10 is the same as that described in connection with the ampule 45.

In Fig. 4 the small ampule shown at 101 30 illustrates the wide range of sizes with which my syringe will coact. When a small ampule is used in my syringe 10 it is not necessary to remove the cap 21, plunger rod 29 and centering member 33 when inserting or removing 35 the ampule from the syringe as the ampule may be inserted or removed through the apertures 14 in the barrel 11.

From the foregoing description it will be apparent that I have provided a novel form 40 of hypodermic syringe which can be economically manufactured, which is simple in construction and highly efficient in use.

Having thus described my invention, I 45 claim:

1. In a syringe adapted to receive an ampule, a barrel, an ampule positioning member movable longitudinally in said barrel, said barrel having a pair of opposed grooves on 50 the inner surface thereof, each of said grooves comprising a straight portion and a flaring portion merging into said straight portion and holding means on said positioning member adapted to actuate in said grooves in said barrel.

2. In a syringe including a barrel adapted 55 to receive an ampule, a pair of oppositely disposed grooves within said barrel, a plunger movable in said barrel, an ampule positioning member mounted to move longitudinally 60 in said barrel, means in said positioning mem-

ber to resiliently engage said barrel, said means including spring pressed members fitted in said grooves in said barrel.

3. In a syringe adapted to receive an ampule, a grooved barrel, a pair of oppositely disposed grooves in said barrel, a cap for said barrel, a plunger rod adapted to move longitudinally through said cap and in said barrel, an ampule positioning member surrounding 70 said plunger rod and adapted to move longitudinally in said barrel independently of said plunger rod, and means to hold said positioning member, said means including spring pressed members movable in said grooves in said barrel.

4. In a syringe adapted to receive an ampule, a barrel, a pair of oppositely disposed grooves in said barrel, a cap for said barrel, a plunger rod adapted to move in said barrel, an ampule positioning member adapted to 75 move longitudinally in said barrel, means in said positioning member to resiliently engage said barrel, said means including a plurality of spring pressed members mounted in said positioning member and adapted to actuate in said grooves in said barrel, a threaded recess in one face of said positioning member and a threaded head on said plunger rod, said threaded head being adapted to be positioned in said threaded recess to thereby join said plunger rod and said positioning member 80 whereby they may be moved together.

5. In a syringe adapted to receive an ampule, a grooved barrel, a cap for said barrel, a plunger rod adapted to move longitudinally 85 through said cap and in said barrel, an ampule positioning member surrounding said plunger rod and adapted to move longitudinally in said barrel independently of said plunger rod, means in said positioning member to resiliently engage said barrel, said last 90 mentioned means including a plurality of spring pressed members mounted in said positioning member and adapted to actuate in the groove in said barrel, said positioning member having a recess in one face and having a threaded recess adjacent the end of said first mentioned recess, an enlarged threaded head on said plunger rod, said threaded head being adapted to be positioned in said threaded recess to thereby join said plunger rod and said positioning member whereby they may be moved together.

6. In a syringe adapted to receive an ampule, a barrel, a cap for said barrel, a plunger rod adapted to move longitudinally through said cap and in said barrel, an ampule positioning member surrounding said plunger rod and adapted to move longitudinally in 100 said barrel, said positioning member having a recess in one face and a threaded recess adjacent the end of said first mentioned recess, a threaded head on said plunger rod, said threaded head being adapted to be positioned in said threaded recess to thereby join said 105

plunger rod and said positioning member whereby they may be moved together, an ampule in said barrel, a stopper in said ampule, said stopper including a projecting member, a recess in said plunger rod head, said plunger rod being adapted when freed from said positioning member to enter said ampule and engage said stopper, said projecting member of said stopper, when said plunger rod engages said stopper, being adapted to be positioned in said recess in said plunger rod head. ¹⁰

In testimony whereof, I hereunto affix my signature.

ARTHUR E. SMITH.
